UNITED STATES PATENT OFFICE.

CHARLES W. POWELL, OF GREEN ISLAND, NEW YORK, ASSIGNOR OF ONE-THIRD TO WILLIAM H. POWELL, OF SAME PLACE.

RAIL-BRAKE FOR STREET-CARS.

SPECIFICATION forming part of Letters Patent No. 442,542, dated December 9, 1890.

Application filed September 24, 1890. Serial No. 365,986. (No model.)

To all whom it may concern:

Be it known that I, CHARLES W. POWELL, a citizen of the United States, residing at Green Island, county of Albany, and State of New York, have invented certain new and useful Improvements in Street-Car Slipper-Brakes, of which the following is a specification.

My invention relates to such improvements; and it consists of the novel construction and combination of parts, hereinafter described and subsequently claimed.

Reference may be had to the accompanying drawings and the letters of reference marked thereon, which form a part of this specification.

Similar letters refer to similar parts in the several figures therein.

Figure 1 of the drawings is a top plan view of a street-car truck supplied with my improved brake with the floor-timbers of the car in position upon the truck and broken away in parts for convenience in illustration. Fig. 2 is a vertical longitudinal section of the truck and lower part of a car, taken along the broken line 2 2 in Fig. 1. Fig. 3 is a vertical section of the truck and lower part of the car, taken along the broken line 3 3 in Fig. 1, showing a modification. Fig. 4 is a top plan view of the brake detached, showing the brake-supporting slide-bar and laterally-projecting bifurcate stud. Fig. 5 is a top plan view of the slideway-block which supports the slide-bar, shown detached.

35 A is the car-truck, which may be of any known desired form, adapted to support a car-body A', (shown in part only,) and be supported by car-wheels A², running upon track-rails A³.

40 A⁴ is the floor of the car, which is supported by the floor-timbers A⁵. The timbers are projected at each end of the car to support the end platforms A⁶, partly broken away. A brake-shaft A⁷, which may be of any known form, is supported in the usual manner upon each platform.

45 My improved brake is of that class which is applied to the track-rails instead of the car-wheels, and when used on street-cars is known as a "slipper-brake."

B is the brake-shoe, which is provided with

a supporting slide-bar B', adapted to slide vertically in a slideway B², contained in the block B³. The block is fixed upon the inner side of the truck-frame by means of the 55 threaded lugs or bolts B⁴ and nuts B⁵, screwed thereon. The slide-bar is provided on its upper end with a shank which supports a coil-spring B⁶. The spring bears at its upper end upon a nut or head B⁷ on the spring-supporting shank and at its lower end upon a cross-bar B⁸, which is secured to the truck-frame and perforated to receive and guide the spring-supporting shank. The resilient force of the spring tends to lift the brake-supporting bar and cause it to slide upward in its slideway, thereby holding the brake in an elevated position above the rail.

50 As a means for forcing the brake down into contact with the rail, I provide a bell-crank lever having the long arm C and the short arm C'. The lever is fulcrumed upon the pivot C², fixed upon the slideway-block B³. The short arm of the lever is provided with a slot C³, adapted to receive the stud C⁴, projecting laterally from the brake-supporting slide-bar. The long arm of the lever may be connected in any known manner, as by chain, with the brake-shaft A⁷.

55 The brake-shaft is supplied with the usual 80 operating-handle C⁵ (indicated by dotted lines in Fig. 1) and a retaining-pawl and ratchet C⁶.

60 By winding the chain upon the brake-shaft in the usual manner the brake-shoe is forced 85 down upon the rail and slips thereon until the car is stopped.

65 Street-cars are required to travel in either direction, and means must be provided for operating the brake from each end of the 90 car. I therefore provide two brakes and brake-operating levers, such as I have described, located opposite each other, one on each side of the car over each track-rail, and connect both brakes by a system of links and 95 levers with two brake-shafts, one at each end of the car.

70 In Figs. 1 and 2 I have shown the long arms of the bell-crank respectively secured by links D and D' with the opposite ends of 100 the connecting-levers D². The latter levers are fulcrumed intermediately of their ends,

as at D³, upon the middle floor-timber D⁴. One end of each connecting-lever is secured to one of the brake-shafts by a chain D⁵, as shown, so that both brakes can be operated 5 at once by either brake-shaft, the bell-crank levers being so arranged that their long arms move in opposite directions toward the opposite ends of the car.

In Fig. 3 I have shown a modified arrangement of connecting-levers, wherein the connecting-levers F F' are fulcrumed intermediately of their ends upon the hangers F², secured to the cross-bar B⁸. One end of the levers is pivoted to the prongs F³ of the bifurcated stud F⁴, which stud is like the stud C⁴, Fig. 2, excepting the prongs. The other ends of the connecting-levers are pivoted together at F⁵. Each of the long arms of the bell-cranks is connected directly with the brake-shaft, as shown in Fig. 3. When the brake shown on the right-hand side of Fig. 3 is forced down upon the rail by turning the brake-shaft shown in such figure, an equal downward movement is transmitted to the other brake through the connecting-levers F and F'. When the left-hand brake is forced downward by the brake-shaft on the end of the car, (not shown in Fig. 3,) a similar movement is communicated to the right-hand brake 25 through the connecting-levers.

The levers F and F' are slotted at their pivotal connections with the stud-forks and with each other to permit a sliding adjustment of the parts when the levers are swung 30 upon the fulcrums.

By having the brake-supporting slide-bar and its slideway B² beveled, as shown in Figs. 4 and 5, the bar is held in place without necessitating the use of a retaining-plate. By 40 having a double lever-connection between the brakes, whenever a downward movement is communicated to one brake a similar movement is communicated through the two levers to the other brake. When desired, the connecting-lever D², Fig. 1, and short link D' on one end of the car may be dispensed with by connecting the longer link D on that end directly with the brake-shaft, as indicated by 45

dotted lines II in such figure, making the short link D' on the other end of the car of a 50 rigid bar, as indicated by the dotted line H'. The brake-shaft on that end of the car having the rigid-bar connection, which is the left-hand end, as seen in Fig. 1, serves to operate one brake by tension upon link D and the other brake by compression, through lever D², 55 upon the rigid bar.

What I claim as new is—

1. In a street-car, a pair of brake-supporting ways secured to the car, in combination 60 with a pair of brakes vertically movable in such ways, one on one side and the other on the opposite side of the car, in the same vertical planes with the car-wheels, a pair of brake-shafts, one at each end of the car, a lever-connection between each brake-shaft and one of the brakes, and lever-connections between the two brakes, whereby a downward movement can be simultaneously communicated to both brakes by either brake-shaft, 70 substantially as described.

2. In a street-car, the combination, with a pair of spring-controlled vertically-movable brakes, one on one side and the other on the opposite side of the car, in the same vertical 75 planes with the car-wheels, of brake-supporting ways secured to the car, a pair of bell-crank levers pivoted upon the car, a connection between the short arm of each crank-lever and one of the brakes, a pair of connecting-levers pivoted intermediately of the ends upon the car at points near the ends of the car on the opposite sides of the bell-cranks, 80 links connecting the long arm of each bell-crank-lever with one end of each connecting-lever, a pair of brake-shafts, one at each end of the car, and a connection between each 85 brake-shaft and a connecting-lever, substantially as described.

In testimony whereof I have hereunto set 90 my hand this 22d day of September, 1890.

CHARLES W. POWELL.
